(57) **CLAIM**

The ornamental design for a power hub with charging station, as shown and described.

DESCRIPTION

FIG. 1 is a top view of a power hub with charging station showing my new design;

FIG. 2 is a right side view thereof;

FIG. 3 is a left side view thereof;

FIG. 4 is a bottom view thereof;

FIG. 5 is a rear view thereof;

FIG. 6 is a front view thereof;

FIG. 7 is a top, front, right side perspective view thereof;

FIG. 8 is a top, rear, right side perspective view thereof; and,

FIG. 9 is a perspective view of the power hub with charging station of FIGS. 1-8 in another configuration.

The broken lines shown in the drawings illustrate portions of the power hub with charging station that form no part of the claimed design.
